His Attorney.

UNITED STATES PATENT OFFICE

WILLIAM P. SUTTON, OF SEMINOLE, OKLAHOMA, ASSIGNOR TO INDIAN TERRITORY
ILLUMINATING OIL COMPANY, OF BARTLESVILLE, OKLAHOMA, A CORPORATION
OF NEW JERSEY

GUARD FOR PROTECTING COUPLINGS OF WELL TUBINGS

Application filed February 23, 1928. Serial No. 256,153.

This invention pertains to guards or protectors for the couplings of tubing or pump rods, such as used in deep wells, such as oil wells.

5 In the operation of such a deep well, the well tubes, pump rods and the like are subject to movement up and down within the casing. It has been found that there is excessive wear on the tubing collars or couplings due to continual friction caused by the tubing moving up and down against the casing.

One of the objects of this invention, therefore, is to provide a guard which may be 15 placed over the tube couplings to protect the same against wear.

Another object is to provide such a guard of soft wearing material, which will wear longer than the metal itself.

20 Another object is to provide such a guard, which may be easily applied and securely held in place.

Another object is to provide such a guard which is cheap to construct and easy to 25 new.

Further objects will appear from the following description, taken in connection with the accompanying drawing, in which—

Figure 1 shows a partial longitudinal section of a guard embodying this invention; and

Figure 2 is a section on line 2—2 of Figure 1.

Referring to the drawing, 1 designates the 35 tube, which is held together by the usual threaded coupling 2. Arranged to be placed over the coupling 2 is a guard 3. This may be constructed of rubber or similar wearing material. This guard is preferably con-

40 structed of a single piece split along one side, as shown in Figure 2, and arranged to be sprung over the tube and coupling. It is provided with a reduced neck 4 at each end, adapted to receive a clamping strip 5, such as 45 a hose clamp, which may be secured at its ends by any suitable fastening, such as a pin 6.

The guard 3 may be generally cylindrical in shape and may be provided at its middle 50 portion with an enlarged chamber 7 adapted

to receive the coupling 2, which it should fit snugly and interlock therewith to prevent endwise movement. As the tubes 1 are often constructed with an upset portion 8 at the joints, the interior bore of the guard 3 may 55 have its end portions formed so as to fit this upset portion of the tube, as illustrated in Figure 1. The guard may then be clamped tightly to the tube 1 so that there will be no liability of its moving on the tube. 60

It will be seen that this invention provides a simple and economical device for protecting the couplings of the tubes where they rub against the casing 10. It has been found in practice that a rubber guard of this 65 type is easily and quickly applied, and that it wears longer than a metal guard. Accordingly, not only is the tube protected, but the wear on the well casing is also reduced to a minimum. The rubber guard also reduces any tendency to abrasion or cutting at the points of contact with the casing, as would be the case with a metal guard. Consequently, not only is the wear of the casing 70 reduced, but the friction involved in operation of the pump is also reduced and the cost of operating decreased correspondingly. This guard can also be used to protect the 75 couplings of pump rods with similar advantages.

It is obvious that various changes may be made, within the scope of the appended claims, in the details of construction without departing from the spirit of this invention; it is to be understood, therefore, that 85 this invention is not limited to the specific details shown and described.

Having thus described the invention, what is claimed is:

1. In well tubing composed of sections 90 joined by couplings, a coupling protector, comprising, a split sleeve adapted to be sprung over the coupling and tubing sections and having a central part adapted to cover the coupling and having end portions adapted to engage the tubing sections, and means for holding said sleeve in place. 95

2. In well tubing composed of sections 100 joined by couplings, a coupling protector, comprising, a split rubber sleeve having a

central cavity adapted to receive the coupling and end portions adapted to engage the tube, said sleeve being split to permit springing the same over the coupling.

5 3. In well tubing composed of sections joined by couplings, a coupling protector, comprising, a split rubber sleeve having a central cavity adapted to receive the coupling and end portions adapted to engage the tube, said sleeve being split to permit springing the same over the coupling, and a clamp for securing said sleeve in place.

10 4. In well tubing composed of sections joined by couplings, a coupling protector, comprising, a sleeve of soft wearing material having an enlarged internal cavity adapted to cover and interlock with the coupling and having end portions adapted to engage the tubing sections, and means for holding said sleeve in place.

15 5. In well tubing composed of sections joined by couplings, a coupling protector, comprising, a sleeve of soft wearing material having an enlarged internal cavity adapted to cover and interlock with the coupling and having end portions adapted to engage the tubing sections, and clamps encircling the ends of said sleeve adapted to hold the same in place.

20 30 6. In well tubing composed of sections joined by couplings, a coupling protector, comprising, a split sleeve adapted to be sprung over the coupling and tubing sections, said sleeve having a central part adapted to cover the coupling and having end portions adapted to engage the tubing sections, and means for holding said sleeve in place.

25 40 7. In well tubing composed of sections joined by couplings, a coupling protector, comprising, a split sleeve adapted to be sprung over the coupling and tubing sections, said sleeve having a central part adapted to cover the coupling and having end portions adapted to engage the tubing sections, and clamps encircling the ends of said sleeve adapted to hold the same in place.

45 In testimony whereof I affix my signature this 16 day of February, 1928.

50 WILLIAM P. SUTTON.
